UNITED STATES PATENT OFFICE

ARTHUR E. SMALL, OF CHICAGO, ILLINOIS, ASSIGNOR TO P. H. MURPHY COMPANY, OF NEW KENSINGTON, PENNSYLVANIA, A CORPORATION OF PENNSYLVANIA

LOAD LIFTING DEVICE FOR RAILWAY CARS

Application filed May 28, 1930. Serial No. 456,575.

The device relates to railway freight cars and comprises means forming a part of the roof structure which provides places for attaching load lifting devices, such load lifting devices being used to move heavy articles into and out of the car or move such articles within the car or to place one part of the load over another part, such as double decking automobiles.

10 The connecting member or beam extends longitudinally of the car and is preferably located adjacent the center of the car or may be positioned near the side plate or one near each side plate, or if desired, may be located 15 in both or in all such positions and still come within the scope of this invention. It may be desirable to raise the load simultaneously from more than one point. The beams may extend the full length of the car and reinforce 20 each and every carline or they may simply include a plurality of carlines and be located as desired. The beams are preferably spaced apart from the roof to provide a space so a chain or rope may be thrown over the beam 25 to support a block and tackle or differential chain or other device.

In the drawing:

Fig. 1 is a vertical transverse section through a railway car roof construction provided with a lifting beam construction embodying my invention,

Fig. 2 is a vertical longitudinal section through the car roof on the line 2—2 in Fig. 3,

Fig. 3 is a fragmentary section on an enlarged scale similar to Fig. 1 of the ridge portion of the roof with the running board structure omitted,

Figs. 4 and 5 are views similar to Figs. 2 and 3, respectively, showing a modified lifting beam construction, Fig. 4 being a sectional view on the line 4—4 in Fig. 5,

Figs. 6 and 7 are similar views of another modified lifting beam construction, Fig. 6 being a sectional view on the line 6—6 in Fig.

45 7; and

Figs. 8 and 9 are similar views of another modified lifting beam construction, Fig. 8 being a sectional view on the line 8—8 in Fig. 9.

50 The drawing shows my improved load lift-

ing device applied to the standard A. R. A. car roof for freight cars, which consists of a channel shape carline 2 comprising substantially vertical walls 3 having lateral flanges 4 at the upper margin of each vertical wall 55 and a plurality of roof sheets 5 secured to said flanges with certain of said sheets overlapping the channel of the carline. This construction forms a box so that it is impracticable to attach anything to the walls 3 of the carlines on account of the difficulty of getting at the inside head of a rivet (or the nut of a bolt) to remove or replace it. This is a serious condition in building new cars and also in repairing cars. Furthermore, makes it quite difficult to apply a load lifting beam 60 to cars already built.

In my arrangement I attach the load lifting beam 7 to the flanges 4 of the carlines 2 by means of brackets which are secured to 70 the carlines by the same rivets 8 which secure the roof sheets 5 to the carlines. To apply my device to existing equipment it is merely necessary to remove and replace a few of the roof sheet rivets 8.

Fig. 1 illustrates the relation of a load lifting beam 7 to the other parts of the car, such as the side plates 10, carline 2, roof sheet 5 and running boards 11.

In Figs. 2 and 3 each load lifting beam 7 is 80 supported by a bracket 13 secured to the carline by the roof sheet rivets 8 and the bracket 13 is provided with a flange 14 upon which the load lifting beam rests. The load lifting beam is spaced apart from the roofing to provide a space to throw a rope or chain over the load lifting beam but the beam is preferably positioned with the lower portion (15) thereof not lower than the bottom of the carline 16 so as not to restrict the clear vertical 85 space in the car. The bracket 13 is made wide enough, as shown in Fig. 3, to accommodate a plurality of roof sheet rivets to provide the necessary strength. A connector 18 may be positioned below the carline and secured to 90 the beams on the opposite sides of the carline and also to the brackets so as to secure cooperation between adjacent beams.

Figs. 4 and 5 show a modified form where- 95 in the load lifting beam 20 is suspended from 100

the carline by the same rivets 8 which hold the roof sheets 5 to the carline. This beam is deflected to provide a space 21 between the upper part of the beam and the roof sheet 5 so as to permit a rope or chain to be thrown over the beam. The beam is preferably channel shape with flanges 23 at its upper margins, which channel is flattened out and offset upwardly, as at 24, at each end of the beam to provide a wide attachment to the carline, as shown in Fig. 4.

Figs. 6 and 7 show a modified form wherein the beams 30 are suspended from the roof sheet rivets 8 by the brackets 31, each bracket being formed to have an engagement with a wall 3 of the carline so as to resist the tendency of the load lifting beams to shift longitudinally of the car. The beams are also extended so that their ends (32) respectively engage the walls of the carline to further resist the longitudinal shifting of the beam. I prefer also to use the connector 34 to secure the beams on opposite sides of the carline together. This construction provides an arrangement wherein a compact, rigid connection of the load lifting beams to the carline is provided. The connector also strengthens the beam to carry a vertical load because it provides a beam semi-restrained at its ends.

Figs. 8 and 9 show a modified form wherein in a stirrup 40 is provided to support the load lifting beam 41 from the roof sheet rivets 8.

35 While I have shown channel shaped beams, it is understood that any other shape beam may be used and still come within the scope of the invention.

The accompanying drawing illustrates the preferred form of the invention, though it is to be understood that the invention is not limited to the exact details of construction shown and described, as it is obvious that various modifications thereof, within the scope of the claims, will occur to persons skilled in the art.

I claim:

1. In a railway car, the combination of a U-shaped carline having lateral flanges at its upper margins, roofing, means securing said roofing to said flanges, a bracket secured to said flanges by said means, and a load lifting beam supported by the bracket.

55 2. In a railway car, the combination of a U-shaped carline having lateral flanges at its upper margins, roofing, means securing said roofing to said flanges, a bracket secured to said flanges by said means, and a load lifting beam supported by the bracket, said load lifting beam being spaced apart from said roofing.

60 3. In a railway car, the combination of a U-shaped carline having lateral flanges at its upper margins, roofing, means securing said roofing to said flanges, a bracket secured

to said flanges by said means, and a load lifting beam supported by the bracket, said load lifting beam being spaced apart from said roofing and positioned with its lower parts not lower than the bottom of the carline.

4. In a railway car, the combination of a U-shaped carline having lateral flanges at its upper margins, roofing, means securing said roofing to said flanges, a bracket secured to said flanges by said means having a substantially vertical portion in contact with one of said walls, and a load lifting beam supported by the bracket.

5. In a railway car, the combination of a plurality of U-shaped carlines with substantially vertical walls having lateral flanges at their upper margins, a roofing, means securing said roofing to said flanges, a bracket on each side of each carline and secured to the flanges thereof by said means, a plurality of aligned load lifting beams supported by said brackets with their opposite ends in contact with the adjacent carlines, and a connector connecting the adjacent ends of the beams on opposite sides of the carlines.

6. In a railway car, the combination of spaced apart U-shaped carlines having lateral flanges at their upper margins, roofing, means securing the roofing to the flanges, and a load lifting beam secured to the flanges of said carlines by said means, said beam being offset to provide a space between the beam and the roofing.

7. In a railway car, the combination of spaced apart U-shaped carlines having lateral flanges at their upper margins, roofing, means securing the roofing to the flanges, and a U-shaped load lifting beam having its ends secured flatwise to the flanges of said carlines by said means, said ends of said beam being offset to provide a space between the beam and the roofing.

8. A railway car construction comprising side plates connected by channel-shaped carlines with outstanding flanges at the tops of their side walls, roof sheets supported on the flanges of said carlines and covering the channels therein, means for securing the roof sheets to the flanges of said carlines, brackets secured to the carline flanges by the means for securing the roof sheets thereto, and a load-lifting beam extending longitudinally of the car between carlines with its ends supported on the brackets and secured thereto.

ARTHUR E. SMALL.
